UNITED STATES PATENT OFFICE.

IRA C. CATTON, OF BRIMFIELD, ILLINOIS.

RAIL-TIE AND RAIL-FASTENER.

971,118.

Specification of Letters Patent. Patented Sept. 27, 1910.

Application filed March 5, 1910. Serial No. 547,392.

To all whom it may concern:

Be it known that I, IRA C. CATTON, a citizen of the United States, residing at Brimfield, in the county of Peoria and State of Illinois, have invented certain new and useful Improvements in Rail-Ties and Rail-Fasteners, of which the following is a specification.

My invention relates to certain new and useful improvements in ties and rail fasteners, by means of which a rail support and fastener are provided that will cheapen the cost of such appliances and provide efficient means for the purpose designed.

More particularly, my invention relates to a metal tie having a special form adapted to render more efficient, ties of the same general character and at the same time adapted in form to facilitate the proper seating and supporting of the fastener; to fasteners having general application to metal ties in various forms adapted to be locked thereto and to properly secure the rail upon the tie and to brace it against lateral movement and vertical separation between the rail and tie.

Referring to the drawings, Figure 1 is a plan view showing a practical application of my improved tie and rail fastener; Fig. 2 is a sectional view through the tie and rails, showing the means of applying the fasteners; Fig. 3 is a sectional view on the line *a—a* of Fig. 1; Fig. 4 is a perspective view showing a section of the tie with the rail secured thereto by means of the fastener; Fig. 5 is a perspective view showing in detail one form of the fastener; Fig. 6 is a perspective view showing another form of the fastener; Fig. 7 is also a detail view showing still another form of the fastener; and Fig. 8 is a perspective view showing the application of still another form of the fastener to secure the rail to the tie.

The tie is designed to be made in any suitable form and may be in the form shown in Fig. 1 and the other figures of the drawing in which the I-beam is employed. The main longitudinal body thereof is designated as *A* and is provided with lateral projections on either side, indicated at *B*. These lateral projections may be of any suitable or desired length and serve to extend the bearing support for the rails and also assist in safeguarding against a rocking motion of the tie, which in practice has the effect to embed it in its earthen support, also the lateral projections serve to assist in

preventing longitudinal shift of the tie. The ties are also formed with proper openings in the upper face thereof to facilitate the proper seating of the rail fastener therein and particular reference to such openings will be hereinafter made. The fastener is designed to be seated within openings in the tie and to bear over the bottom flange of the rail and to extend parallel along the vertical web of the upper end thereof in close relation with the rail head, substantially as shown in Fig. 2. I have referred to these fasteners as *C* and they may be made of any suitable material and may be properly reinforced to give them sufficient strength. The fasteners are provided with a depending lug or lugs as *a* provided with a slot or slots as *b*, said lugs being adapted to depend through openings in the top of the tie as at *c* and to be locked in position by means of a key as *d*. This key may be formed with a roughed side or bottom portion if desired, so that when it is properly seated within the slots of the fastener it may more readily retain its place or it may be held in place by means of a key in the end thereof or, in fact, may be secured against dislodgment in any suitable manner. The key is designed to be made of such length and form that when properly placed it will hold the fastener down upon the lower flange of the rail, and as it is applied, the lower face of the body thereof is designed to bear away slightly from the upper face of the tie so that as the fastener may be slightly worn by contact with the rail, by causing the wedge to penetrate a little deeper into the slots the lost motion may be readily taken up. The rear end of the fastener is formed with an offset and a rearwardly extending part as *e* adapted to enter an opening in the tie as at *f* and the rear end of the fastener is extended in a parallel line with the face of the tie as at *g* for the purpose of covering the opening. The projection *g* is formed with a slight incline so that it may be readily entered into the slot in the tie.

In the application of the form of fastener shown in Figs. 1 to 6, the depending lugs *a* are adapted to bear, one upon either side of the middle web of the tie and in substantially close bearing relation therewith. However, when it is designed to apply the fastener to a rectangularly formed, hollow metal tie, the lugs may be placed thereon in

any suitable position to accommodate the fastening of the same, to such tie, and the wedge may be of sufficient length to extend the entire width of the tie so as to penetrate the openings in the lugs wherever they may be situated. Obviously, bolts may be substituted in place of the wedged keys herein shown.

In Fig. 7, I have shown a form of fastener in which the lugs are perforated in a transverse direction from that shown in the other figures of the drawing. In this form, the keys are adapted to be entered in the direction of the length of the tie and in this form will serve the same purpose as in the application shown in the other figures of the drawing.

In Fig. 8, I have shown the application of the principle of my device, wherein a fastener referred to as D appears. In this form, it is designed in the application that the upper face of the tie shall be slotted and that the fastener may be inserted in the manner shown in Fig. 8 and may be bolted and secured to the tie by means of a bolt as shown. In fact, the fastener may be made in many forms and applied in many ways without departing from the principle of my invention.

30 The tie may be specially formed with depending lugs as E to accommodate their being placed upon stringers, as for use in bridge work, and will serve a useful purpose in such connection.

35 It will be observed that in constructing the fastener C with the lugs α depending through openings in the upper face of the tie, there is provided an abutting surface for the edge of the bottom flange of the rail that will prevent any lateral movement and will prevent the ordinary and usual wedging effect of lateral movement of the rail upon the ordinary form of fasteners that are in commercial use. It will be observed that the 45 fastener C would have to be completely detached before the lateral bearing effect of the lugs would be destroyed.

What I claim and desire to secure by Letters Patent is:

50 1. In a railway tie and rail fastener, the combination with a tie provided with lateral projections therefrom and with perforated seats for parts of a rail fastener, of a rail fastener plate provided with an upwardly 55 projecting portion adapted to bear against the rail, with a hook like lug at the rear portion thereof adapted to enter and be supported in an opening in the tie and with a downwardly projecting locking lug adapted 60 to be seated in a perforation in the tie and in abutting relation with the lower flange of the rail and suitable means for fastening the locking lug to hold the rail fastening plate in place.

65 2. In a device of the class described, the

combination with a tie provided with laterally extending projections to form a bearing support in connection with the main body of the tie for a rail, a rail fastener provided with a plate having an upwardly 70 turned forward end adapted to engage the rail and with downwardly and outwardly bent rearward extremities adapted to engage openings in the tie and fastening lugs depending from the under face of the plate 75 and adapted to be seated within openings in the tie and a suitable bolt or key for securing the plate in position to fasten the rail upon the tie.

3. In a device of the class described, the 80 combination with a metal tie having a central rib and laterally extended flange projections therefrom and laterally extended portions adapted to form, in conjunction with the main tie, a support for the rail, of 85 a rail fastener formed of a plate provided with an upwardly turned portion adapted to engage the rail and with a rearwardly extended portion adapted to engage perforated seats in the tie and with fastening lugs depending from the lower portion of the plate adapted to be seated within openings in the tie and in position to abut against the lower flange of the rail, and provided with a key 90 seat therethrough and a key adapted to fit 95 within the key seats in the fasteners, substantially as described.

4. In a device of the class described, the combination with a railway tie, of a fastener formed of a plate having an upwardly 100 turned portion adapted to engage a rail, and having downwardly and rearwardly extending portions adapted to hook within openings in the tie and with abutting and fastening lugs extending downwardly from the 105 lower face thereof adapted to be seated within openings in the tie and to abut against the lower flange of the rail, and suitable means for securing the fastening and abutting lugs in position to securely hold the rail 110 upon the tie.

5. A railway tie and rail fastener comprising a tie substantially in I-beam form provided with lateral projections therefrom in substantially the same form as the tie and 115 provided with openings in the upper face thereof adapted for seating lugs, a rail fastener formed of a plate provided with an upwardly turned portion adapted to engage the rail, with downwardly and rearwardly 120 extending portions adapted to be seated within perforations in the tie and with abutting and fastening lugs depending from the lower portion thereof adapted to be seated within openings in the tie and provided 125 with a key seat therein, and a suitable key for securing the fastening lugs in connection with the tie, substantially as shown.

6. In a device of the class described, the combination with a railway tie provided 130

with perforations therein, of a rail fastener consisting of a plate provided with an upwardly turned and suitably reinforced portion adapted to bear upon the rail flange, to extend upwardly along the web thereof and to meet the lower edge of the top flange of the rail and with angularly formed rearward extensions therefrom adapted to engage perforations in the tie and with fastening lugs depending from the lower portion of the plate and adapted to be seated within per-

forations in the tie and provided with a key seat therein and a key adapted to secure the fastening lugs in connection with the tie, substantially as described.

15

In testimony whereof I have affixed my signature in presence of two witnesses.
